(57) **CLAIM**

The ornamental design for a transmission line post assembly, as shown and described.

DESCRIPTION

FIG. 1 is a perspective view of the transmission line post assembly according to an embodiment;

FIG. 2 is a front view thereof;

FIG. 3 is a left side view thereof, the right side view being a mirror image thereof;

FIG. 4 is a rear view thereof;

FIG. 5 is a top view thereof;

FIG. 6 is a bottom view thereof;

FIG. 7 is an enlarged perspective view of a region “7” of FIG. 1;

FIG. 8 is an enlarged front view of a region “8” of FIG. 2;

FIG. 9 is a perspective view of the transmission line post assembly according to another embodiment;

FIG. 10 is a front view thereof, the rear view being a mirror image thereof;

FIG. 11 is a left side view thereof, the right side view being a mirror image thereof;

FIG. 12 is a top view thereof;

FIG. 13 is a bottom view thereof;

FIG. 14 is an enlarged perspective view of a region “14” of FIG. 9; and,

FIG. 15 is an enlarged front view of a region “15” of FIG. 10.

The broken lines shown in the drawings are for the purpose of illustrating portions of the transmission line post assembly that form no part of the claimed design. The broken lines

(Continued)

encircling detail portions in FIGS. 1-2, 7-10, and 14-15 illustrate the boundaries of the detail portions, and form no part of the claimed design.
